TABULATING MACHINE

William W. Lasker, Brooklyn, N. Y., assignor to Remington Rand Incorporated, New York, N. Y., a Corporation of Delaware

Application October 3, 1929. Serial No. 397,082

2 Claims. (Cl. 101—96)

My invention relates to card-controlled tabulating machines which automatically print columns of items on record-sheets, and by which each column is printed with a unit that forms a component of a fixed row of accounting and printing units that act on a sheet supported by a rotary platen and framework in which the platen is mounted, which framework is motionless while the machine prints and while it performs a series of operations wherein any unit then printing items prints them all in one column. The invention relates especially to the combination with the row of accounting and printing units contained in a card-controlled tabulating machine, of means comprising relatively adjustable paper supports for causing any unit of the row to print in any of several columns on record-sheets used in producing records of various forms and having, if desired, ruled columnar fields distinguished by printed headings. A record-sheet may be joined to other record-sheets, called also work-sheets, all forming a continuous web or multiple sheet or strip with printed forms thereon and with interleaved carbon strips.

In machines of the type disclosed in patent to Powers #1,245,502, and to which the devices of my invention are herein shown attached, there are usually a plurality of independent adding mechanisms, each being associated with its own printing instrumentalities. Thus, when a card record discloses a number of classifications of data, it is possible to allot an individual adding and printing mechanism to each classification. By so doing, separate totals of each classification may be simultaneously accumulated on the multiple record sheets from a succession of record cards that may be fed through the machine.

The construction of the present invention includes means whereby records pertinent to the various adding and printing mechanisms may be printed simultaneously on a plurality of superposed work sheets or strips, (with interposed carbon strips between them) so that each item will be printed in substantially the same location of each of the work sheets, while permitting a simple and speedy adjustment of such sheets to be made without destroying the relation between them when changing the columnar relationship between the work sheets and any particular totalizer and printer, or when advancing the assembled sheets.

An object of the invention is also to provide means that permit the use of assembled work sheets for cooperation with certain totalizer and printing units of an accounting machine, while

an independent record or tally sheet is being simultaneously used in conjunction with other totalizer and printing units, allowing of differential columnar adjustment without affecting the assembled relation of the work sheets.

A further object of the invention consists in the provision of supporting, guiding and feeding means for a plurality of assembled work sheets and in the provision of an independent paper roll with means whereby adjustments for various widths of work sheet, and for paper roll may be made without disturbing the feeding characteristics, and whereby the relativity of either the paper roll or work sheets may be changed in respect to the adding totalizers and printing mechanisms, without affecting the feeding mechanism or assembled relation of the work sheets.

To the above and other ends which will hereinafter appear, my invention consists in the features of construction, arrangements of parts, and combinations of devices set forth in the following description and particularly pointed out in the appended claims.

In the accompanying drawings, wherein like reference characters designate corresponding parts in the different views:—

Fig. 1 is a fragmentary, detail, side view with parts in section of that portion of the paper feeding carriage of the Powers tabulating machine with which the devices of my invention cooperate.

Fig. 2 is a detail perspective view showing the adjustable lower support and side guides for controlling the passage of the assembled work sheet and interleaved carbon strips from the support tray to the feeding mechanism.

Fig. 3 is a fragmentary, front view of the machine with parts broken away and showing the devices of my invention attached to the carriage, together with some of the printing instrumentalities, etc.

In order to better explain the purpose of my invention, I have disclosed in the accompanying drawings, in addition to my novel mechanism, certain parts of the printing and paper feeding instrumentalities of the Powers accounting machine, as shown in said Patent #1,245,502.

As an example of the work that is performed through the instrumentalities of my invention I refer to the method of summarizing the value, class, district, and sales office records of shipments made from a central establishment to branch offices. In such a case, a plurality of duplicate records are required to be made, whereby data is immediately furnished to different department heads giving full information concern-

ing the outgoing merchandise. The general sales manager uses his record for general information. The billing dept. may use its record for invoicing. The stock clerk from his record prepares data 5 for the production manager, while a record may be sent to the receiving clerk as a debit memorandum to check against the goods when received. A tally slip bearing the record of totals only is made at the same time to furnish a record of 10 the value of the day's gross shipment value.

Assuming the foregoing conditions, the usual card is punched from the records of a sales order, price lists and extended value, and according to the particular requirements, certain of the total- 15 izer and printing units are selected to operate in conjunction with cross folded continuous strips of forms arranged with interleaved carbon paper and suitably perforated to permit the severing of each group of superposed sheets having 20 registering printed forms thereon after same have been printed and passed through the machine.

My construction provides a suitable tray or basket to support the supply or cross folded stack 25 of forms to be fed through the machine, and such tray and other features of the construction are laterally positioned with respect to the selected printing and totalizer units and the tally roll may also be suitably adjusted to its particular 30 printing mechanism and totalizer.

The need to simultaneously control the printing and analyzing unit associated with the tally roll with the particular totalizer allotted to the corresponding value to be recorded on the multiple 35 forms, is met by so-called "Y wire" connections in the connection box of the tabulating and accounting machine commonly used in such machines and fully described in the pending application Ser. No. 97,915 of Merkel, filed March 27, 1926.

40 A common platen for the tally roll record and the work forms or sheets is actuated through a common actuating means well known and found in Powers accounting machines.

45 My novel mechanism is carried by the usual carriage so that any lateral adjustment of the carriage would result in moving the tally roll and cross folded forms carried thereby, bodily with respect to the printing and totalizer units, to get certain relative adjustments.

50 Beyond this, it is possible to separately locate the tally roll with respect to the cross-folded forms, giving a very flexible and simple means of adjustment, or the carriage with my novel unit attached is laterally movable, so that the 55 machine may be speedily adapted to any columnar and tally-roll position for cooperation with selected printing and totalizer units and without changing in any way the paper feeding, printing, and totalizer sections.

60 The upper portion of the cover of the well known Powers accounting machine is represented by the reference numeral 1, and is shown in Fig. 1 as seen from the right hand side of the machine, and a portion thereof is broken away to expose the rock shaft 2^a and pinion 2 mounted thereon. These members are operated from the main operating shaft of the machine (not shown) through the arm 3 and link 4, shown in dotted lines. The pinion 2 meshes with a pinion shaft 6 extending substantially throughout the length of the platen carriage and carried between the side plates 7 thereof.

70 The platen carriage is constructed and mounted as follows: Attached to the end supporting frames 8 of the accounting machine are the

brackets 9 which have slots 10 that receive holding screws 11, which slot and screw connection serves to permit a fore and aft adjustment of the brackets 9 and parts attached thereto with respect to the side frames 8 of the machine. Each bracket 9 has a foot piece 12 turned at right angles to the body portion thereof and each foot piece has suitable holes to receive screws 13 which connect a fixed cross rail or supporting plate 14 to the brackets 9 and thus provide a track on which the paper carriage may be slidably adjusted to different set positions. A main carriage plate 15 has riveted thereto an upper guide bar 16, and a lower guide bar 17 which extend the whole length of plate 15, and are slightly thicker than plate 14. The guide bars 16 and 17 are spaced apart to receive the fixed supporting plate 14 between them and guide the carriage along said plate. Closure plates 18 which over-lap the opposite side of the plate 14 from that to which the plate 15 is secured, are fastened by screws 19 to the guide bars 16 and 17.

The carriage end plates 7 are also provided with right angle inwardly extending flanges 20 having holes through which rivets 21 pass to secure plates 7 to the slidable plate 15. Extension arms 7^a are secured by screws 22 to the side plates 7 and have open ended slots or bearings 23 at their upper ends to receive and support a tally roll supporting rod or shaft 24. This rod has peripheral grooves 105 therein to engage the arms 7^a and thus prevent axial movement of the rod 24 in its bearings in the arms 7^a. A cross or tie rod 25 is fixedly mounted between the arms 7^a at a point somewhat lower than the rod 24 and serves to carry the adjustable 110 horizontal paper supports and side guides, each designated as a whole by the reference numeral 26. Each of these guides, as shown at Fig. 2, is suitably formed with an inclined sheet supporting portion 26^a and a vertical flange 27 which constitutes a side edge guide. Fixedly secured to these vertical flanges 27 are hubs 28 that are mounted on and may be adjusted along the rod 25. Thumb screws 29 enable the guides 26 to be held in any positions to which they may be adjusted along the 115 rod, such adjustment being made to suit the width of the work sheets that they are to be guided between the flanges or side guides 27. The downward extension 30 on each guide 26 is so disposed as to lead the pack of multiple work sheets down 120 to the platen 31 at the introductory or rear side thereof. The platen is carried on the revolving shaft 32 carried in bearings provided in the carriage end plates 7. Pressure feed rolls 33 loosely turn in cradle arms 34 and direct the multiple 125 work sheets from the guides 26 around the platen up in front thereof past the printing line. A fixed rod 35 mounted between the plates 7 supports at suitable positions depending arms 36 which at 130 their upper forwardly off-set ends have outward extending lugs to which the upward tensioned springs 37 are attached. Each arm 36 has a lower forwardly extending arm which carries a screw stud 38 on which is loosely mounted the rocking cradle arms 34. A flattened shaft, 39, also rotatable in bearings in plates 7, has its flattened side adjacent the lower finger 40 of each of the arms 36 and serves, when turned by its finger piece 39^a, to cam the arms 36 away from the platen 31 against the tension of springs 37, to thus relieve 135 the gripping pressure of the feed rolls, so that the work sheet may be adjusted on the platen.

A suitable feed ratchet 41 connected to the platen is advanced step-by-step by the feed or line spacing pawl 42 carried by the double ended 140

rocker arm or lever 43 mounted to turn on the axis of the platen. Fixedly mounted on the end of the pinion shaft 6 is the arm 44 and a connecting link 45 is pivoted at its upper end to this arm 44, and is pivotally connected at its lower end to the lower end of the rocker arm 43. This provides a driving connection between the pinion shaft 6 and the platen 31 so that the latter is revolved in a clockwise direction, as seen in Fig. 1, by increments of movement dependent upon the extent of rocking movement imparted to the pinion shaft 6.

Since the driving pinion 2 has no lateral movement but meshes with the pinion shaft 6, it is obvious that inasmuch as the platen 31, the side plates 7 supporting same, and the extensions 7^a supporting the shafts 24 and 25 and guides 26, are mounted on the sliding plate 15, any work sheet carried thereby may be laterally adjusted to different set positions with respect to the feed controlling pinion 2 without impairing the feeding of the work sheet around the platen 31. In order to attain the purposes of the present invention, such characteristics must be maintained in Powers accounting machines, when columnar printing is carried out, and when this printing is to be made on either continuous rolls of paper that can be carried by the rod 24 or on continuous webs or sheets of limited length that can be conveniently supported by the carriage without encumbrance. In Fig. 3 there is presented more or less diagrammatically, and respectively marked, A, C, D, F, G, the outline of five of the different groups of printing type commonly used in conjunction with the plurality of accumulators, (usually seven) found in the Powers accounting machine. Due to the breaks in Fig. 3 only five of the seven printing groups usually employed are represented, the B and E groups coming in the broken away portions. The purpose of this plurality of accumulators and printing devices, is to afford a means of segregating the totals of different values that are simultaneously collected from the perforated record cards that are fed to the machine for the automatic analysis of this data. In performing this work it has been customary to provide work sheets of such width as to accommodate the entire range of type from group A to group G, and the plotting of Fig. 3 is intended to illustrate the relativity of several of such type groups, which are immovable laterally, and the platen and work sheets set to coact therewith.

While a platen of adequate length is provided to extend completely across the faces of the printing type of all groups A, B, C, D, E, F, G, difficulties arise when the work sheets are of narrower width than would include all groups simultaneously, and where two more work sheets (arranged side-by-side) are fed through simultaneously, in order to collect the respective data on different and independent work forms according to the classification of detail and the uses to which the collected data is put. There has arisen a demand for collecting printed data, part of which is required in multiform copies on continuous webs, and at the same time a tally record of one or more of the classifications as recorded in certain columns of the multiform copies, for audit and other purposes. To this end a tally roll such as is shown at 46 is provided. The single narrow strip Y leading from this roll passes over a tie rod 46^a by which it is supported in its passage to the platen. The tally strip is carried round the platen, with the loose end 47 passing out after extending up from the platen, as shown in Fig. 1, and is simultaneously fed with the group of

multiform work sheets or webs. In this class of work, possibly data collected from the printing instrumentalities of groups D and F might be desired on the multiform sheets, while the data of group F would be required to be printed on the tally strip. By mechanism disclosed in the hereinbefore mentioned application of Merkel the group A printing instrumentalities would simultaneously record the same data as is being recorded by group F. In the event that a second tally record was required of group D, then a printing unit acting on a strip carried by another tally roll suitably positioned on rod 24 could be made to record the second tally record. Because of the desirability of providing multiple copies, the various work sheets or webs X with the forms printed thereon are preferably assembled with interleaved carbon paper or strips of a width and length equal to the work sheets X which are much easier to handle than a number of individual single form sheets that would require frequent and troublesome introduction in and removal from the machine. In the present construction I prefer to employ long continuous sheets that are cross folded transversely of the length of the sheets, the distance between folds corresponding to the length of each form. This method of supplying the work sheets, while facilitating the handling in some respects, presents other difficulties relative to the carrying of the stack of folded forms, particularly so when a speedy re-arrangement thereof with reference to the selected printing instrumentalities and accumulators is found necessary, in order to accommodate the requirements called for by the sheet columnar rulings. To aid in making these adjustments, I have devised in addition to the features hereinbefore referred to, the attachment now to be described, so that large stacks of folded forms can be as readily handled. In Figs. 1 and 3, 48 represents the two end frames, preferably of aluminum castings, which constitute the supporting members for a basket or tray formed by securing gauze or perforated sheet metal around and across the three edges of each of the frames 48, as shown at 49 in Fig. 1. Fig. 1 illustrates the perforated metal in section and exposes to view a stack 50 of multiform continuous webs or form sheets, it being understood that each fold may be supposed to include a plurality of layers of paper with interposed carbon paper, as many as six or seven layers, sheets or webs of paper being employed at times. Brace rods 51, 52 rigidly connect and maintain the frames 48 spaced apart at their upper ends, and serve to carry the guide rolls 53 and 53^a which rotate thereon, and over which the multiple work sheets are led in the direction of the arrows in Fig. 1. The multiple web is led from the stack 50 in the tray over the lower roll 53, the supporting and side guides 26, round the platen 31, and thence over the upper roll 53^a to be discharged to a receiving point where the operator may sever the sheets at perforated lines provided at the folds. The frames 48 are provided with forwardly extending arms 48^a at the forward end of each of which is a boss having a hole or bearing opening through which the carriage rod 25 passes to afford a means for anchoring the tray to the carriage and for affording a lateral adjustment of the tray on the carriage. A thumb screw 54 received in a tapped opening in one of the bosses of an arm 48^a is used to secure the tray in its position of lateral adjustment on the carriage. In order to relieve the strain on rod 25, an angle

bracket 55, Figs. 1 and 3 has its vertical extension riveted to the vertical perforated metal wall adjacent the accounting machine cover, and to the horizontal bracket extension is secured a shouldered stud 56 which carries a roller 57 retained on the stud by the large headed screw 58.

This roller 57 bearing against a vertical side of the accounting machine cover, provides a support and rolling contact that relieves the strain on the rod 25 when a heavy stack of work sheets is supported on the tray 49, and makes the lateral sliding adjustment of the tray on the rod 25, when the thumb screw 54 is backed up, an easy matter.

15 Whenever necessary the tray 49 may be adjusted in relation to the platen 31, and it also may be necessary to adjust the guides 26 on the rod 25 to accommodate the width of the work sheets and to ensure the latter being controlled accurately with respect to the particular groups of type that are being employed in recording the data. Furthermore, the tally roll 46 on rod 24 may also be adjusted relative to both the guides 26 and the work sheet tray 49, 20 by the adjustable collars 59 with their thumb screws 60.

Thus, it is seen that I provide means that readily permit the setting of printing instrumentalities for producing printed records on a plurality of sheets from a plurality of printing units simultaneously and in a differential manner, and insuring a uniform spacing of the successive printed items, notwithstanding the use of a bulky stack of work sheets in continuous strip form.

35 The construction is such that it may be made to accommodate itself to a wide range of uses and may be readily set up to take care of the varying conditions of use in which the machine may be employed. For example, the detachability 40 of the supporting rod or shaft 24 enables one or more tally rolls to be readily placed thereon, or all of said tally rolls may be removed from the supporting rod when not required. Various widths of work sheets may be employed and the 45 guiding devices 26 which coact therewith may be adjusted accordingly and the work sheets may be variously brought to different positions along the platen for coaction with different printing groups, and the carriage may be adjusted to and 50 maintained set in different positions with the same object in view.

From the foregoing description it will be seen that I have provided simple, inexpensive and efficient means for carrying out the purposes of 55 the present invention.

60

65

70

75

Various changes may be made in the construction, and some of the features thereof may be employed without others, without departing from my invention as it is defined in the accompanying claims.

What I claim as new and desire to secure by Letters Patent, is:—

1. In a machine of the class described having a plurality of sets of printing type, each of said sets of type having its type arranged in consecutive serial order and in progressive denominational orders, and automatic means including a record for selecting type from the groups of sets of type for a printing impression, the combination of a laterally adjustable frame for supporting a platen for carrying record material constructed and arranged to simultaneously receive a printing impression from a plurality of type in any set of type, and means for supporting, guiding, and adjusting a pre-arranged-pre-printed record material web including a container for said record material attached to the frame for supporting the platen, mutually adjustable web guides for said record material, and optionally adjustable means for locating said laterally adjustable frame in any position within a predetermined range whereby webs of differing arrangements may receive printing in optionally selectable positions.

2. In a machine of the class described having a plurality of groups of sets of printing type, each of said sets of type having its type arranged in consecutive serial order and in progressive denominational orders, and means including a record for selecting type from the groups of sets of type for a printing impression, the combination of a laterally adjustable frame for supporting a platen for carrying record material constructed and arranged to simultaneously receive a printing impression from a plurality of type in any set of type, and means for supporting, guiding, and adjusting a series of record material webs including a container for one record material web attached to the frame for supporting the platen, mutually adjustable web guides for one of said record material webs, and optionally adjustable means for locating said laterally adjustable frame in any position within a predetermined range whereby a series of webs of differing arrangements may receive printing in optionally selectable positions at the will of the operator.
